UNITED STATES PATENT OFFICE.

CHARLES I. E. MASTIN, OF MIDLAND PARK, NEW JERSEY.

PACKING.

Application filed May 27, 1920. Serial No. 384,750.

To all whom it may concern:

Be it known that I, CHARLES I. E. MASTIN, a citizen of the United States, residing at Midland Park, in the county of Bergen and State of New Jersey, have invented certain new and useful Improvements in Packings, of which the following is a specification.

This invention relates to packing materials, and particularly to packing materials formed elongated, as in strips, and used for purposes where one of the packed parts moves relatively to the other, as a piston rod in its gland, and it is therefore necessary or desirable to provide the packing with means to resist wear or other undesirable results incident to such movement. My object is to provide an elongated packing which is well adapted for use, for example, as a packing of the particular class above indicated and which will have a high degree of flexibility, so that it may be entered in packing relation to the parts to be packed with the greatest possible facility.

In the accompanying drawing, Figure 1 is a perspective view of the improved packing piece;

Figure 2 is an elongated sectional view thereof, the section being taken on the line 2-2 in Figure 1;

Figure 3 shows in perspective the blank from which the body of the packing is formed;

Figure 4 is a side elevation, partly in longitudinal section, of the core of the packing;

Figure 5 is a perspective view of a modified form of the packing, and Figures 6 and 7 similar views of parts thereof;

Figures 8 and 9 are perspective views of other modified forms of the packing; and

Figure 10 shows how the packing may be flexed and twisted.

I prefer to form the body of the packing of a combination of some stout fabric and rubber, the fabric being in layers *a* and the rubber *b* cementing the various layers together, as by being interposed between the layers. The fabric layers are shown by solid lines and the rubber by broken lines in Figure 3. The layers of fabric will best be cut on the bias, as indicated in said figure.

Having in this way formed an elongated pad or the like such as is shown in Figure

3, the pad is bent longitudinally into channeled form. This will bring its lateral edges 55 or faces *c* into such position that in the ultimate product if the packing is to be used in contact with some moving part, as a piston rod, the edges of the fabric layers may face and be in contact with such mov- 60 ing part.

In Figure 4 is shown a spiral core *d* composed of a substance which, with my principal object in view, is adapted to resist wear to better advantage than the body of 65 the packing. The chief component of the substance forming this core is in the present instance graphite. It will be an advantage, as will be indicated, if this spiral core is so formed that its convolutions will produce an exterior spiral channel *e*. The core is flexible, and in the preferred form is practically without elasticity; it is both a wear-resistant and a lubricant.

Having shaped the body to the channeled 75 form, as above explained, and having provided the core *d*, I place the core in the groove or channel of the body and then introduce these thus-assembled parts into a press, wherein they are subjected to pressure and the rubber of the body is vulcanized, it being understood that the rubber as it exists in the body previous to this is in the uncured state. The product will have the form shown in Figure 1 (instead of being square, it may have some other form, as rounded at the back, as shown in Figures 8 and 9), and as the spiral in the present instance is assumed to be round in end elevation, the edge portions *c* of the body will 80 more or less overlap it and so hold it in place. One important result of subjecting the channeled body of yielding material and the core, formed in effect with exterior portions in relief or as projections due to the 85 channel *e*, to pressure in a press or mold is that the portions in relief, marked *f* in Figure 4, form recesses *g* in said body, the parts then setting in the final product in a state of interlock with each other. 100

Instead of arranging the core so as to seat directly against the body, I may interpose a cushion between the core and body, that is, back of the core. This cushion may be formed in various ways. Thus, in Figures 105 5 to 7 it is composed of a rubber strip *h*

against which the core directly bears and a strip *i*, formed say of fabric treated with rubber, to form a backing for the strip *h*; or as shown in Figure 8 there may be a suitable yielding strip *j* to form a seat for the core and a filler back of the strip composed of layers of fabric *k* and rubber arranged with its fabric layers set with their edges presented to the strip *j*; or as shown in Figure 9 there may be a suitable yielding strip *l* to form a seat for the core, a filler *m* like the filler shown in Figure 8 and arranged back of the strip *l*, and back of the filler *m* a strip *n* of soft rubber. After the pad has been formed and channeled as described in reference to Figures 1 to 4 the parts constituting the core and cushion are placed therein, whereupon the thus-assembled parts are placed in the press and subjected to pressure and vulcanizing, the edge portions of the pad, which then becomes a casing for the core and cushion, overlapping the core the same as in the form first described and so holding the contained parts in place.

Even after the spiral core becomes worn through, as an incident of the friction of a piston or other moving part in contact therewith, which is possible, the parts of the core left remaining as partial volutes will keep their original positions in the body of the packing due to the recess or bed each such volute forms therein for itself at the time of compressing and vulcanizing.

So far as I am aware it is new to provide, in a packing, a body structure of yielding material and, in any way embedded therein (whether as a core or not), a wear-assuming means of less yielding material, or a lubricating means, including spiral or other whorls, turns or convolutions formed each about an axis which is substantially parallel with a working face (as A, Figures 1, 2, 5, 8 and 9) of the packing and having their exteriors presented to said faces.

Having thus fully described my invention,

what I claim as new and desire to secure by Letters Patent is:—

1. A flexible packing member including a yielding body having a working face and a flexible less yielding spiral core contained in the body and having its exterior presented to said face.
2. A flexible packing member including a yielding body having a working face and a flexible unyielding spiral core contained in the body and having its exterior presented to said face.
3. A flexible packing member including a yielding body having an exterior working face and a flexible elongated core contained in said body and having a surface portion, extending longitudinally thereof and appreciably less in width than the core is thick, exposed at said face, said body otherwise concealing the core.
4. A flexible packing member including a yielding body having an exterior working face and a flexible elongated spiral core contained in said body and having an exterior surface portion extending longitudinally thereof and appreciably less in width than the core is thick, exposed at said face, said body otherwise concealing the core.
5. A packing member including a channeled yielding body and a core arranged longitudinally of and in the channel of the body and exposed longitudinally by said channel, said body at one side of the channel overlapping the core and thus holding the core in the channel.
6. A packing member including a channeled casing, an elongated core arranged longitudinally of and in the channel of the casing and exposed by the channel, and a cushion of material more yielding than the core arranged in the channel back of the core.

In testimony whereof I affix my signature.

CHARLES I. E. MASTIN.
